3

According to the dyeing instruction given in Example 1, there is obtained on fibres of polyethylene terephthalic acid glycol ester a reddish yellow shade of very good fastness to wet processing, subliming and light.

When the diazo components listed in the following table are coupled with 1-(tetrahydrothiophene-1'-dioxi-de-[3'])-3-methyl-pyrazolone-(5), dyestuffs are obtained which dye polyester fibres in the following shades according to the method given in Example 1:

Example No.	Diazo component	Shade of the dyeing on poly-ester fibres	10
3	1-amino-4-chlorobenzene	reddish yellow.	
4	1-amino-4-methoxybenzene	very intense red- dish yellow.	15
5	1-amino-2-methoxy-5-methylbenzene	Do.	
6	4-amino-5-methoxy-oxathiol-S-dioxide	orange.	
7	1-aminobenzene-4-carboxylic acid-ethyl ester.	reddish yellow.	
8	1-aminobenzene-2-sulfonic acid-phenyl ester.	Do.	
9	1-amino-3-cyanobenzene	yellow.	20
10	1-amino-2-nitrobenzene	reddish yellow.	
11	1-amino-2,4-dichloro-6-nitrobenzene	intense reddish yellow.	
12	1-amino-4-nitrobenzene	reddish yellow.	
13	1-amino-3-nitrobenzene	yellow.	
14	1-amino-2,4-dinitrobenzene	yellowish orange.	
15	1-amino-2-chloro-5-trifluoro-methylben- zene.	yellow.	25
16	1-amino-2-nitro-4-methylbenzene	reddish yellow.	
17	2-aminobenzthiazole	Do.	

When the diazo components listed in the following table are coupled with 1-(tetrahydrothiophene-1'-dioxaide-13')-3-phenyl-pyrazolone-(5) (M.P. 220° C.), dye-stuffs are obtained which dye aromatic polyester fibres according to the dyeing method given in Example 1 in the following shades:

Example No.	Diazo component	Shade of the dyeing on poly-ester fibres
18.....	1-amino-2-chloro-4-nitrobenzene.....	reddish yellow.
19.....	1-amino-2-nitro-4-ethoxybenzene.....	intense reddish yellow.
20.....	1-amino-4-nitro-2-methoxy-5-methylbenzene.	reddish yellow.

When 1-(tetrahydrothiophene-1'-dioxide-[3'])-pyrazolone-(5)-carboxylic acid ethyl ester-(3) (M.P. 228-229° C.) is used as coupling component, the diazo components listed in the following table yield dyestuffs which dye aromatic polyester fibres according to the dyeing method given in Example 1 in the following shades:

Example No.	Diazo component	Shade of the dyeing on poly-ester fibres
21.....	1-amino-2-chloro-4-nitrobenzene.....	greenish yellow.
22.....	1-amino-2-nitro-4-ethoxybenzene.....	intense reddish yellow.
23.....	1-amino-2-chloro-4-nitro-5-methoxybenzene.	reddish yellow.
24.....	6-methyl-2-(4'-aminophenyl)-benzthiazole.	yellowish orange.

The diazo components listed in the following table are coupled with 1-(tetrahydrothiophene-1'-dioxide-[3'])-pyrazolone-(5)-acetic acid ethyl ester-(3) (M.P. 122° C.). Dyestuffs are obtained which according to the dyeing method given in Example 1 may be dyed on polyester fibres in the following shades:

Example No.	Diazo component	Shade of the dyeing on polyester fibres
25.....	1-amino-2-chloro-4-nitrobenzene.....	yellow.
26.....	1-amino-2-nitro 4-ethoxybenzene.....	intense reddish yellow.
27.....	1-amino-4-nitro-2-methoxy-5-methylbenzene.	reddish yellow.

4

We claim:

1. A monoazo dyestuff corresponding to the formula

wherein R_1 stands for a radical selected from the group consisting of the benzene series and 2-benzthiazolyl, R means a member selected from the group consisting of hydrogen, a lower alkyl, carboxylic acid lower alkyl ester and lower alkylene carboxylic acid lower alkyl ester, R and R_1 being free of sulfonic and carboxylic acid groups.

2. The monoazo dyestuff corresponding to the formula

3. The monoazo dyestuff corresponding to the formula:

4. The monoazo dyestuff corresponding to the formula:

5. The monoazo dyestuff corresponding to the formula:

6. The monoazo dyestuff corresponding to the formula:
